Angus R. Gross Inventor
Alexander Dowell Attorney

UNITED STATES PATENT OFFICE.

ANGUS R. GROSS, OF BALTIMORE, MARYLAND.

DESIGN FOR A COMBINATION SIGNAL LIGHT FOR AUTOMOBILES.

Application filed May 17, 1923. Serial No. 6,176. Term of patent 14 years.

To all whom it may concern:

Be it known that I, ANGUS R. GROSS, a citizen of the United States, residing at Baltimore, State of Maryland, have invented a new, original, and ornamental Design for a Combination Signal Light for Automobiles, as shown in the accompanying drawings, forming part of this specification.

In said drawing, Fig. 1 is a rear view of

the design for combination signal light. Fig. 2 is a top plan view thereof, and Fig. 3 is a side view thereof.

I claim—

The ornamental design for a combination signal light for automobiles, substantially as shown.

ANGUS R. GROSS.
